US0D1017052S

(12) United States Design Patent (10) Patent No.: US D1,017,052 S
(45) Date of Patent: * Mar. 5, 2024

(54) POSTURE GARMENT

(71) Applicant: Hempvana, LLC, Miami Beach, FL (US)

(72) Inventors: Ajit Khubani, Saddle River, NJ (US); Mohan Rajasekaran, Watertown, CT (US)

(73) Assignee: Hempvana, LLC, Miami Beach, FL (US)

() Term: 15 Years

(21) Appl. No.: 29/820,371

(22) Filed: Dec. 21, 2021

(51) LOC (14) Cl. 24-99

(52) U.S. Cl.

USPC D24/190

(58) Field of Classification Search

USPC D24/126, 127, 128, 171, 183, 184, D24/188-192, 200, 206, 212-214; D29/101.2-101.5, 113, 120.1, 121.2, D29/122-124; D2/614-617, 625-627, D2/634, 639, 640, 705, 708, 714, 985, D2/994

CPC A41D 13/0525; A41D 13/0531; A41D 2500/20; A61F 13/148; A61F 5/028; A61F 5/03; A61F 5/24; D04B 21/20
